DESIGN FOR A COFFEEPOD OR LIKE ARTICLE

Application filed August 6, 1930. Serial No. 36,576. Term of patent 7 years.

To all whom it may concern:

Be it known that I, GUSTAV B. JENSEN, a subject of the King of Denmark, and a resident of the city of New York, in the county and State of New York, have invented a new, original, and ornamental Design for Coffee Pot or like article, of which the following is a specification, reference being had to the accompanying drawings, forming a part thereof.

In the drawings:

Fig. 1 is a front elevation of the coffee pot showing my new design;

Fig. 2 is a side elevation of the same; and

Fig. 3 is a top plan of the same.

Referring more particularly to the draw-

ings, reference character 1 represents the coffee pot as it appears mounted on a base or pedestal 6, and provided with side handles 2 and 2', top piece 3, spigots 4 and 4', and spigot handles 5 and 5'.

The dominant feature of my design consists in the general configuration of the body 1, substantially as shown by the solid lines in the drawings.

Having thus shown and described my invention, I claim:

The ornamental design for a coffee pot or like article, substantially as shown and described.

GUSTAV B. JENSEN.
